UNITED STATES PATENT OFFICE

2,129,173

CAR COUPLER CENTERING DEVICE

Garth G. Gilpin, Riverside, Ill., assignor, by mesne assignments, to Standard Railway Equipment Manufacturing Company, a corporation of Delaware

Application June 5, 1937, Serial No. 146,578

3 Claims. (Cl. 213—21)

The invention relates to railway cars and more particularly to centering device and emergency support for railway car couplers and is an improvement upon the device covered by my Patent No. 1,658,120 granted February 7, 1928.

The object of the device is to provide a fabricated structure to support a swingable carrier for a railway car coupler comprising a plurality of rolled steel parts reduced to a unitary structure by welding, which parts are shaped so that they can readily be formed from flat plates between dies in a reciprocating press.

Another object is to arrange the associated parts so that the places of welding are accessible to the welder and also accessible for removing the welded material to disassemble the structure.

Another object is to form the associated parts so that they will be very strong for their weight.

Another object is to form and assemble the component parts so that there will be no pockets to hold water (or moisture) which would cause corrosion.

Another object is to form the complete structure so that the same swingable links and coupler carrier may be used which is now standard construction on a great many railroads.

Another object is to materially reduce the weight of the structure in comparison with the cast metal striking castings now in general use.

30 In the drawings:

Fig. 1 shows a front elevation of a railway car equipped with my improved device.

Fig. 2 shows a section on line 2—2 of Fig. 1 on the right side and a section on line 3—3 of Fig. 1 on the left side.

Fig. 3 is a side elevation of Fig. 1.

Fig. 4 is a section on line 4—4 of Fig. 3.

Fig. 5 is a perspective view of the assembled structure with the carrier, swingable links and trunnion pockets omitted.

Fig. 6 shows the trunnion pocket in perspective.

In the form of the invention illustrated the car is provided with the usual center sill construction 2 which is extended to the ends of the car and 45 supports the draft gear or draft rigging so that the spaced apart portions are sometimes called draft sills. The draft gear chiefly is not shown.

The end and upper part of each sill is cut out to form an upper notch 4 and a striking plate 5 fits into the upper notches and is welded to the draft sills at 6 and 7. This striking plate is reinforced by the horizontally disposed metallic plate 8 which is welded to the striking plate and to the draft sills.

55 The end and lower part of each draft sill is cut

out to provide a lower notch 10 and the angular brackets 12 are welded to each sill adjacent the upper portions 14 of the notches and adjacent the vertical margins 15 of the notches. These angular brackets 12 provide supports for one end of 5 the trunnion links 16 and also provide a hood to protect the upper ends of the trunnion links 16.

An angular tie member 20 extends between and is welded to the draft sills 2 at 22, which angular tie member is provided with an outwardly projecting flange 24 at the lower margin thereof. This member 20 provides a strut-tie between the two draft sills 2 so that it acts in compression or tension to retain the draft sills in proper relation to each other. The face plates 30 are welded to 10 the ends of the draft sills (32) and to the flange 24 of the tie member at 34, and also preferably to the striking plate 5 at 36. These face plates 30 form supports for the upper ends of the trunnion links 16. 20

A lug 38 is welded to each of the angular brackets 12 and a similar lug 40 is welded to each of the face plates 30. The trunnion pockets 42 are provided with projections 43—44 forming recesses 45 which straddle the lugs 38 and 40 to 25 hold the trunnion pocket against lateral displacement and the rivet 46 or other means otherwise holds the trunnion pockets in place.

The coupler centering device comprises the usual coupler carrier 50 swingably supported by 30 the trunnion links 16 which pivotally engage pockets in the carrier and also pivotally engage the trunnion pockets 42. The carrier 50 is provided with lugs 52 to hold the coupler in proper relation to the carrier. The carrier 50 and links 35 16 form no part of this invention.

The striking plate angular tie member 20 and the two face plates 30 form a rectangular frame for the coupler shank which ties the ends of the two draft sills 2 together. The angular tie member 20 also provides an emergency coupler support. In case the centering device should fail the coupler would rest on the upper edge of the coupler tie member 20 and not fall to the track. 40

The accompanying drawings illustrate the preferred form of the invention though it is to be understood that the invention is not limited to the exact details of construction shown and described, as it is obvious that various modifications thereof, within the scope of the claims, 45 will occur to persons skilled in the art.

I claim:

1. A fabricated structure to support a swingable carrier for a railway car coupler comprising spaced apart draft sills, a notch in the end and 55

- lower part of each sill, an angular bracket welded to the outside of each sill adjacent the upper and vertical margins of said notches, a lug welded to the outside of each of said brackets, an 5 angular tie member extending between and welded to said sills which is provided with an outwardly projecting flange at the lower margin thereof, a face plate extending outwardly beyond the sill and welded to the end of each sill 10 and to the flange of the tie member to form a housing, and a lug welded to the inside of each of said face plates opposite the first mentioned lugs for supporting trunnion pockets.
2. A fabricated structure to support a swingable carrier for a railway car coupler comprising spaced apart draft sills, a notch in the end and lower part of each sill, an angular bracket welded to the outside of each sill adjacent the upper and vertical margins of said notches, a lug welded 15 to the outside of each of said brackets, an angular tie member extending between and welded to said sills which is provided with an outwardly projecting flange at the lower margin thereof, a face plate extending outwardly beyond the sill and welded to the end of each sill, said face plate being welded 20 to the flange of the tie member to form a housing, and a lug welded to the inside of each of said face plates opposite the first mentioned lugs for supporting trunnion pockets.

welded to the inside of each of said face plates, and trunnion pockets having recesses therein which straddle said lugs to hold the trunnion pockets against lateral displacement.

3. A fabricated structure to support a swingable carrier for a railway car coupler comprising spaced apart draft sills, a lower notch in the end and lower part of each sill, an angular bracket welded to the outside of each sill adjacent the upper and vertical margins of said notches, a lug 10 welded to the outside of each of said brackets, an angular tie member extending between and welded to said sills which is provided with an outwardly projecting flange at the lower margin thereof, an upper notch in the end and upper 15 part of each sill, a striking plate fitting in said notches and welded to said sills, a face plate extending outwardly beyond the sill and welded to the end of each sill, said face plate being welded to said striking plate, and to the flange of the 20 tie member to form a housing, and a lug welded to the inside of each of said face plates opposite the first mentioned lugs for supporting trunnion pockets.

GARTH G. GILPIN. 25
